UNITED STATES PATENT OFFICE.

JOHN C. KONRAD, OF NEW YORK, N. Y., ASSIGNOR TO CLARENCE
WAINRIGHT WOOD, OF SAME PLACE.

DESIGN FOR A BODY FOR DELIVERY-WAGONS.

SPECIFICATION forming part of Design No. 28,752, dated May 31, 1898.

Application filed February 19, 1898. Serial No. 670,978. Term of patent 7 years.

To all whom it may concern:

Be it known that I, JOHN C. KONRAD, a citizen of the United States of America, and a resident of the borough of Manhattan, in the city of New York and State of New York, have invented and produced a new and original Design for a Body for Delivery-Wagons, of which the following is a specification, reference being had to the accompanying drawings, forming part thereof.

The figure of the drawing is a side view of the body of a delivery-wagon, showing said new and original design.

The leading or distinguishing feature of this design is the general outline of the wagon-body in side view, as represented in said drawing and hereinafter described. Said general outline comprises a peculiarly-shaped arch *a* beneath the seat portion, with sharp angles *1* and *2* at both abutments, an ogee front line *3*, terminating at top in a substantially rectangular corner *4*, a curved line *5*, extending rearward and downward from said corner, and a slightly oblique line *6*, connecting said line

5 with the rear abutment angle *2*. Beginning ²⁵ in front of said arch *a* and conformed thereto raised borders *b*, *c*, *d*, and *e* extend along the bottom of the body, up the rear edge, along the roof-line, and downward, with conformation to a cut-away front edge, inclosing ³⁰ a side panel *p* of irregular shape.

The lower rear corner *7* of the body is substantially rectangular, and the upper rear corner *8* projects rearwardly, the rear line and said raised border *c* having a rearward trend. ³⁵ A penciled border-line on the panel *p*, following its outline, is represented at *9*, and a lamp-window within said panel at *10*.

Having thus described said design, I claim as new and original and desire to patent under this specification—

The design for a body for delivery-wagons, substantially as shown and described.

JOHN C. KONRAD.
